CLAIM

The ornamental design for a twisted conical brush handle, as shown and described.

DESCRIPTION

FIG. 1 is a perspective view of a brush with a first twisted conical brush handle;

FIG. 2 is a front elevation view of the brush handle of FIG. 1;

FIG. 3 is a rear elevation view of the brush handle of FIG. 1;

FIG. 4 is a left elevation view of the brush handle, of FIG. 1;

FIG. 5 is a right elevation view of the brush handle of FIG. 1;

FIG. 6 is a top plan view of the brush handle of FIG. 1;

FIG. 7 is a bottom plan view of the brush handle of FIG. 1;

FIG. 8 is a perspective view of a brush with a second twisted conical brush handle;

FIG. 9 is a front elevation view of the brush handle of FIG. 8;

FIG. 10 is a rear elevation view of the brush handle of FIG. 8;

FIG. 11 is a left elevation view of the brush handle of FIG. 8;

FIG. 12 is a right elevation view of the brush handle of FIG. 8;

FIG. 13 is a top plan view of the brush handle of FIG. 8; and,

FIG. 14 is a bottom plan view of the brush handle of FIG. 8.

The portions of the Figures shown in broken lines illustrate environmental structure and form no part of the claimed design.

1 Claim, 14 Drawing Sheets
